UNITED STATES PATENT OFFICE.

JOHN MILTON BENJAMIN, OF BEVERLY, MASSACHUSETTS, ASSIGNOR TO UNITED SHOE MACHINERY COMPANY, OF PATERSON, NEW JERSEY, A CORPORATION OF NEW JERSEY.

SOLE-SLOTTING MACHINE.

1,153,886.

Specification of Letters Patent. Patented Sept. 21, 1915.

Application filed February 14, 1911. Serial No. 608,534.

To all whom it may concern:

Be it known that I, JOHN M. BENJAMIN, a citizen of the United States, residing at Beverly, in the county of Essex and State 5 of Massachusetts, have invented certain Improvements in Sole-Slotting Machines, of which the following description, in connection with the accompanying drawings, is a specification, like reference characters on 10 the drawings indicating like parts in the several figures.

This invention relates to machines for operating upon the soles of boots and shoes and is herein illustrated in connection with 15 a machine for producing a transverse groove or slot across a sole which is to be used in a shoe having a spring heel.

In the manufacture of turn shoes having spring heels it is customary to cut a slot or 20 groove across the flesh side of the sole at the junction of the heel and shank portions to receive the beveled end of the spring lift and to facilitate the bending of the sole at that point; and the general object of the 25 present invention is to provide a simple and effective power-actuated machine for accomplishing this result.

Accordingly one feature of the present invention consists in the provision with a 30 knife and a feed roll for advancing a piece of stock thereto of a yieldingly mounted idle roll for supporting the stock during the feeding operation. And preferably the feed roll comprises a section or member 35 the periphery of which corresponds in outline to the outline of the edge of the knife; and the idle supporting roll is adjustable toward and from the feed roll. With such a construction the driving mechanism for 40 the supporting roll which would necessarily be of a complicated nature in order to provide for adjustment of said roll is dispensed with, and at the same time pieces of stock of different thickness may be operated upon.

45 In order to facilitate the ease with which the cutting operation is performed another feature of the invention consists in the provision in a machine of the class described of a grooving knife the axis of which is arranged at an oblique angle to the line of feed of the stock; and in order to provide clearance for said knife the angles of the bevels which form the edges thereof are preferably such that during the cutting operation the 50 bevels lie in planes which are parallel to the

direction of feed of the stock. With a knife so constructed and arranged not only will the cutting operation be facilitated but the force required to feed the stock forward will be less than would otherwise be necessary. 60

Another feature of the invention consists in the provision in a machine of the class described of a knife, means for adjusting said knife and a retaining means for holding said knife in place, the parts being so constructed and arranged that the knife may be removed from the machine and replaced therein without disturbing said adjustment. In the illustrated embodiment 70 the knife is fixed to a cylindrical holder which may be adjusted angularly in a socket by a rack, and longitudinally by a screw which is carried by a retaining cap, said cap being threaded upon the end of the socket. 75 When, therefore, the retaining cap has been unscrewed, the cap, screw, holder and knife may be drawn out of the socket. This is particularly convenient when it is desired to sharpen the knife, since it is evident that 80 after such sharpening the parts can be replaced without disturbing the adjusting members, it being necessary merely to screw the retaining cap once more into place.

These and other features of the invention 85 including certain details of construction and combinations of parts will be explained in connection with an illustrative machine and will be pointed out in the appended claims.

Referring to the accompanying drawings, 90 Figure 1 is an end elevation of a machine in which the present invention is embodied; Fig. 2 is a section on the line 2—2, Fig. 1, illustrating the means of adjusting the knife angularly; Fig. 3 is a detail perspective 95 showing the knife in operation upon a sole; Fig. 4 is a detail perspective of the knife; Fig. 5 is a rear elevation of the machine; and Fig. 6 is a detail perspective of a portion of the sole after it has been operated upon. 100

Extending laterally from the head 1 is a bracket 3 having a bore which receives the stem 5 of a yoke between the arms 7 of which is mounted a stock supporting roll 9, 105 said roll being rotatable on a shaft 10 which is held in the arms of the yoke. The arms 7 of the yoke are provided with extensions, one of which is shown at 11, and these extensions uphold a supporting table 13 which 110

carries adjustably mounted thereon an edge gage 15, said gage being curved downwardly at its rear portion and being provided with an extension 17 which engages the upper 5 surface of the margin of the sole during its passage through the machine. The stem 5 has a portion 19 of reduced diameter whereby a shoulder 21 is formed, and this portion of reduced diameter has threaded on its end 10 a handhold 23 which serves in conjunction with the spring 25 to raise and lower the yoke and with it the roll and table, said spring having one end abutting against the shoulder 21 and the other against the end of 15 a counterbore in the extension 3. In order to prevent the stem 5 from moving angularly about its axis, a guide rod 27 held in a socket in one of the arms 7 by means of a pin 29 is slidably mounted in a bore in a lug 20 31 which extends laterally from the bracket 3. With this construction it will be noted that there is provided a supporting roll and table yieldingly mounted and adjustable in unison and that the roll is not connected, in 25 any way with the other parts of the machine and is consequently a freely, revoluble, idle supporting roll.

Mounted in bearings in the head 1 and carrying fast and loose pulleys 34 and 36 is 30 a driving shaft 33 on which is fixedly held the feed roll. This roll comprises two cylindrical end sections or members 35 and 37 which engage the stock at each side of the knife and a central section 39 having an outline 35 to correspond to the outline of the edge of the knife and arranged to engage that portion of the stock which is removed by the knife.

In the illustrated embodiment of the invention the edge of the knife is substantially V-shaped, and hence the central section or member 39 is frusto-conical. Because of the shape of the section 39 the skiving which is removed by the knife is crowded between 40 said knife and section only along a line determined by the intersection of the plane of the base of said section with the surface of the stock; and consequently the knife may be set close in toward the bite of the section 45 39 without causing objectionable binding of the skiving which is being removed.

Attention is here directed to the simplicity of the feeding mechanism. The stock is held firmly against the upper feed roll by 50 the idle roll 9 and the table 13, the outer sections or members 35 and 37 engaging the stock at each side of the knife and the central section engaging the skiving as it is being removed from the stock. It is thus possible 55 to cause the knife to make clean uniform cuts without the necessity of providing a more or less complicated mechanism for rotating the adjustable lower roll.

The head 1 of the machine is provided at 60 its upper portion with flanges 41 which form

vertical guideways in which are mounted the slides 43 of a carrier 45, said carrier being provided with a cut-away portion spanned by a cross bar 47 through which is threaded an adjusting screw 49, this adjusting screw being rotatable in a flange 51 of the head but held from longitudinal movement with respect thereto, a lock nut 53 being provided to insure that the carrier 45 shall be held securely in adjusted position. 75

The carrier 45 is formed with a cylindrical socket 55 having a slot 57 communicating with the interior thereof and having formed on its outer end exterior screw threads 59. Adapted to coöperate with the screw threads 80 59 is a cap 61, and rotatably mounted in the cap but held from longitudinal movement with respect thereto is an adjusting screw 63 provided with a knurled head 65. The threaded end of this screw engages the rear 85 end of a cylindrical knife holder 67 and serves to adjust said knife holder longitudinally of its axis.

In order to provide for angular adjustment of the knife holder, the socket 55 is 90 provided with a hollow boss 69 in which is mounted a rack 71 which engages teeth 73 formed on the knife holder. One end of the rack is formed with a knurled head 75 and the other is of reduced diameter and 95 threaded through the end of the boss, a lock nut 77 being provided to hold the rack in adjusted position. The forward end of the knife holder 67 is provided with a cylindrical bore 79 with which a slot 81 communicates, and in this bore and slot the knife is adapted to fit tightly and to be held by friction. The knife, as shown in Fig. 4, comprises a rib 83 in the form of a mutilated cylinder, said rib terminating in an upright edge 85, and a lateral extension 87 terminating in an edge 89 at an angle to said upright edge. With the construction described above the knife may be raised or lowered by means of the screw 49, may be 100 adjusted longitudinally by means of the screw 63, and angularly by means of the rack 71. It should be noted that these adjusting mechanisms are so constructed and arranged that the knife and holder may be 105 removed from the machine and replaced without disturbing the adjustment thereof. It is necessary merely to unscrew the cap 61 whereupon the knife holder 67 with the knife still held thereby may be pulled from the socket 55, the slot 57 providing the passage for the extension 87 of the knife. 110

By referring to Fig. 2, it will be seen that the point of intersection of the cutting edges 85 and 89 is concentric with the knife 115 holder 67. It is thus possible to adjust the knife angularly without changing the depth of the cut or the location of the deepest portion thereof.

To facilitate the cutting operation the 120

- axis of the socket 55 is arranged at an oblique angle to the bite of the rolls and consequently to the direction in which the stock is fed, and in order to provide proper clearance 5 the rib 83 of the knife adjacent the upright edge 85 is beveled as at 91, the extension 87 being provided with a bevel on its under side as shown in dotted lines in Fig. 4, both of which bevels lie in planes parallel to the direction in which the stock is fed. In the use of the machine the handhold 23 is rotated to accommodate the machine to the thickness of the stock which is to be operated upon, and the screw 49 is turned to regulate the depth of cut. The longitudinal adjustment of the knife is accomplished by turning the screw 63 and the angular adjustment by turning the rack 71. These parts together with the edge gage 15 having been adjusted, power is applied to the shaft 33, and the stock is operated upon as shown in Fig. 3 wherein the stock is indicated at 93 and the portion being removed at 95.
- Although the invention has been set forth in connection with a particular machine, it should be understood that the invention is not limited in the scope of its application to the particular machine shown and described.
- Having thus described the invention, what I claim and desire to secure by Letters Patent of the United States is:
1. A machine of the class described having, in combination, a knife having its edge formed to cut a V-shaped groove in a piece of stock, means for supporting said stock, and means for feeding said stock, said feeding means comprising a roll having a central section to engage the portion of the stock which is removed by the knife and spaced sections arranged to engage the uncut stock on both sides of said knife.
  2. A machine of the class described having, in combination, a knife, a feed roll, means for rotating said feed roll, an idle supporting roll, a supporting table, said roll and table being adjustable in unison, and yielding means for supporting said roll and table.
  3. A machine of the class described having, in combination, a knife having its edge shaped to cut a groove in a piece of stock, means for supporting said stock, and means for feeding said stock, said feeding means comprising members for engaging the stock at each side of the knife and a member having its periphery formed to correspond to the shape of the knife edge and arranged to engage that portion of the stock which is removed by the knife.
  4. A machine of the class described having, in combination, a knife having its edge shaped to cut a groove in a piece of stock, yielding means for supporting said stock, and means for feeding said stock, said feeding means comprising members for engaging the stock at each side of the knife and a member having its periphery formed to correspond to the shape of the knife edge and arranged to engage that portion of the stock which is removed by the knife.
  5. A machine of the class described having, in combination, a grooving knife, a stock supporting table, a stock supporting roll carried by said table, a feed roll comprising end members arranged to engage the stock on each side of the knife and a central member having its periphery formed to correspond to the shape of the edge of the knife and arranged to engage that portion of the stock which is removed by the knife, yielding means for causing said feed roll and supporting roll to approach each other, and means for actuating said feed roll.
  6. A machine of the class described having, in combination, a feed roll for advancing a piece of stock, means for rotating said roll, a yieldingly sustained idle supporting roll, a grooving knife having its axis arranged obliquely with respect to the direction in which said stock is fed, means for adjusting said knife vertically, means for adjusting said knife angularly about its axis, and means for adjusting said knife longitudinally.
  7. A machine of the class described having, in combination, a feed roll, means for rotating said roll, a supporting roll yieldingly held, and a grooving knife having beveled edges, the axis of which is arranged obliquely to the direction in which the stock is fed by said rolls, the angles of the bevels which form the edges of said knife being such that said bevels lie in planes parallel to the direction in which said stock is fed.
  8. A machine of the class described having feed rolls for advancing a piece of stock to be operated upon and means for actuating one of said rolls in combination with a knife having its axis oblique to the line of feed, a carrier by which said knife is supported, means for adjusting said knife angularly about its axis and means for raising and lowering said carrier.
  9. A machine of the class described having means for feeding a piece of stock to be operated upon in combination with a member having a socket, a knife holder capable of longitudinal and angular adjustment fitted in said socket, a knife carried by said holder and means acting upon said holder for moving the holder angularly while maintaining the longitudinal adjustment.
  10. A machine of the class described having stock feeding mechanism in combination with a grooving knife, a holder by which said knife is carried, means for adjusting said holder angularly about its axis, means

for adjusting said holder longitudinally, and a holder-retaining member by which one of said means is carried.

11. A machine of the class described having means for feeding a piece of stock to be operated upon in combination with a carrier provided with a socket, a knife holder slideable in said socket, a knife carried by said holder, means for adjusting said holder angularly, a removable retaining member, and means engaging said member for adjusting said holder longitudinally.

12. A machine of the class described having means for feeding a piece of stock to be operated upon in combination with a carrier provided with a cylindrical socket, a knife holder, a knife carried by said holder, a member movable to adjust said holder angularly, a second member movable to adjust said holder longitudinally, and a retaining cap the construction being such that upon disconnecting the cap, the holder and with it the knife and one of the adjusting members may be removed from the machine while maintaining the position of the other adjusting member.

13. A machine of the class described having means for feeding a piece of stock to be operated upon in combination with a socket, a knife holder fitted in said socket and provided on its periphery with teeth, a rack engaging said teeth, and means whereby said rack may be adjusted.

14. A machine of the class described having means for feeding a piece of stock to be operated upon in combination with a holder

provided with a bore and with a slot communicating with said bore, a grooving knife formed with a portion to fit in said bore and with an extension to lie in said slot, and means for supporting said holder.

15. A machine of the class described having means for feeding a piece of stock to be operated upon in combination with a holder provided with a bore and with a slot communicating with said bore, a grooving knife the stock of which is in the form of a mutilated cylinder provided with an extension, said cylinder and extension being adapted to fit in said bore and slot, and means for supporting said holder.

16. A machine of the class described having means for feeding a piece of stock to be operated upon in combination with a grooving knife having its edge formed in two intersecting portions and means for adjusting said knife angularly about the point of intersection.

17. A machine of the class described having a grooving knife and rolls for feeding a piece of stock thereto in combination with an edge gage having an extension to engage the upper surface of the piece of stock, said extension being curved longitudinally in a direction transverse to the axes of said rolls.

In testimony whereof I have signed my name to this specification in the presence of two subscribing witnesses.

JOHN MILTON BENJAMIN.
